Assistant Examiner — Carson Jean Bendel

(57) **CLAIM**

The ornamental design for a shopping cart, as shown and described.

DESCRIPTION

FIG. 1 is a perspective view of a shopping cart showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof; and,

FIG. 9 is an enlarged portion taken from line 9 in FIG. 1. The broken lines indicate enlarged portions of the drawings, and form no part of the claimed design.

1 Claim, 9 Drawing Sheets
